ADJUSTABLE BOOK RACK

John S. Vuici, Grosse Pointe, Mich.

Application August 4, 1959, Serial No. 57,063

Term of patent 14 years

(Cl. D33—2)

FIG. 2

FIG. 3

FIG. 4

Fig. 1 is a top plan view of an adjustable book rack, showing my design.

Fig. 2 is a side elevational view.

Fig. 3 is an end view on an enlarged scale.

Fig. 4 is a fragmentary view taken along the line 4—4 of Fig. 1 and showing a portion of the rack in greater detail.

I claim:

The ornamental design for an adjustable book rack, as shown.
